UNITED STATES PATENT OFFICE.

CHARLES CHAMBERLIN, OF LOWELL, MASSACHUSETTS.

SPINDLE-PROTECTOR FOR CARRIAGE-AXLES.

SPECIFICATION forming part of Letters Patent No. 259,366, dated June 13, 1882.

Application filed February 17, 1881. (No model.)

To all whom it may concern:

Be it known that I, CHARLES CHAMBERLIN, of Lowell, in the county of Middlesex and Commonwealth of Massachusetts, have invented certain new and useful Improvements in Spindle-Protectors for Carriage-Axles, of which the following is a specification.

My invention is in some respects similar to the invention described in Letters Patent No. 231,691, granted August 31, 1880, to John A. Tillinghast; and it consists in a protector provided with a downwardly-enlarged drip-receiver; also, in a protector provided with a downwardly-enlarged drip-receiver and a hole; also, in a protector provided with a downwardly-enlarged drip-receiver and a hole, in combination with a plug; also, in a ring closely fitting over the axle-box and provided at its inner end with an internal annular flange, in combination with said axle-box; also, in a ring closely fitting over the axle-box and provided at its inner end with an internal annular flange and an external annular flange, in combination with said axle-box and a protector provided with a downwardly-enlarged drip-receiver; also, in a ring provided at its inner end with an external annular flange, in combination with a protector having a downwardly-enlarged drip-receiver, all as and for the purpose hereinafter specified.

In the accompanying drawings, Figure 1 is a side view of a part of the axle, the protector, and the hub. Fig. 2 is a side view of the axle and a vertical longitudinal section of the hub, axle-box, protector, and nut. Fig. 3 is an elevation of the end of the protector nearest the hub. Fig. 4 is a vertical longitudinal section of the protector.

A is the axle; B, the spindle, provided with the collar C; D, the hub, and E the axle-box, all of the usual construction, except that the hub is provided with annular grooves to receive the flanges of the protector and nut. At the outer end of the spindle B is a nut, F, which serves the usual purpose of holding the wheel on the spindle, and which also keeps the oil from running out of the axle-box and the dust from getting into the axle-box, said nut being provided not only with the usual circular flange, G, but also with a cylindrical flange, G', which projects from the circumference

of the flange G and enters an annular groove, H, in the outer end of the hub D, thus completely covering and closing the outer end of the axle-box. At the other end of the hub, and surrounding the axle, is the protector I I', provided with a rectangular hole, J, to admit the axle, and a cylindrical flange, K, which enters an annular groove, K', in the inner end of the hub and prevents the entrance of dirt and sand into the inner end of the axle-box E. In these respects my protector is like the one described in the patent above referred to. I also divide the protector horizontally into two segments, but make the upper part or segment, I, smaller than the lower, I', dividing said protector near the top of the axle, so that a part of the hole J is in each segment I I'. I secure the segments together by screws L L', instead of by bolts cast upon the lower segment. I think this construction is better where the protector needs to be fitted to the axle. Now, the inner end of the axle-box is flush with the inner end of the hub, as usual; but I drive a metallic ring, M, over the inner end of the axle-box into the wood of the hub. This ring M fits the axle-box closely, and is provided at its inner end with an internal annular flange, N, which flange, with the end of the axle-box, forms an internal annular chamber, O, in said ring (the chamber may be formed wholly in the ring) to receive a surplus of oil from the axle-box and to prevent said oil from coming in contact with the wood of the hub. Thus I accomplish two very desirable objects—one being that the oil-chamber O makes it unnecessary to oil the wheels more than one-fourth as often, and the other object being the prevention of the deleterious action of the oil upon the wood of the hub, this action being to soften the wood and thereby to loosen the axle-box. As will be seen, the outer diameter of the ring is greatest at its inner end, so that a surplus of oil running out of the chamber O will not follow the ring up to the hub, but will drop from the lowest part of the ring when the wheel is not in motion, or will be thrown by centrifugal force from the greatest external diameter of the ring when the wheel is in motion. The inner end of the ring M, with its enlarged outer diameter, above described, reaches back about to the middle of the protector I I'. Now, the protector is en-

larged downward at the bottom, between the flange K and its inner end or face, to form an oil-receptacle, P, to receive the drip or overflow of oil from the chamber O and to hold the oil away from the wood of the hub. The oil may be removed from the protector by removing the screw-plug Q, or the plug Q may be dispensed with, leaving the hole R open at all times for the oil to run out. With this arrangement there is no danger of getting sand into the axle-box by the splashing of dirt and mud in wet weather, inasmuch as any dirt or water which gets into the sand-box or protector will be prevented by the ring M from entering the axle-box, and may be removed through the hole R, or will run out if the hole be left open. In washing carriages with a hose it will be best to leave plug Q out, and the water will then run out of the protector as fast as poured in, without entering the axle-box.

New axle-boxes may be formed in one piece with the ring M.

I claim as my invention—

1. The protector I I', provided with a downwardly-enlarged drip-receiver, P, as and for the purpose specified.
2. The protector I I', provided with a down-

wardly-enlarged drip-receiver, P, and a hole, R, as and for the purpose specified.

3. The protector I I', provided with a downwardly-enlarged drip-receiver, P, and a hole, R, in combination with the plug Q, as and for the purpose specified.

4. The ring M, closely fitting over the axle-box E, and provided at its inner end with an internal annular flange, N, in combination with said axle-box, as and for the purpose specified.

5. The ring M, closely fitting over the axle-box E, and provided at its inner end with an internal annular flange, N, and an external annular flange, in combination with said axle-box and a protector, I I', provided with a downwardly-enlarged drip-receiver, P, as and for the purpose specified.

6. The ring M, provided at its inner end with an external annular flange, in combination with a protector, I I', having a downwardly-enlarged drip-receiver, P, as and for the purpose specified.

CHARLES CHAMBERLIN.
